UNITED STATES PATENT OFFICE.

MICHEL G. FAGAN, OF TROY, NEW YORK.

IMPROVEMENT IN FURNACES.

Specification forming part of Letters Patent No. **175,059**, dated March 21, 1876; application filed May 5, 1875.

To all whom it may concern:

Be it known that I, MICHEL G. FAGAN, of Troy, in the county of Rensselaer and in the State of New York, have invented certain new and useful Improvements in Reversible-Flue Furnaces; and do hereby declare that the following is a full, clear, and exact description thereof, reference being had to the accompanying drawings, making a part of this specification, in which—

Figure 1 is a perspective view of my furnace with the casing removed. Fig. 2 is a vertical central section of the same upon line *x x* of Fig. 1, which passes from front to rear, and Fig. 3 is a like view upon line *y y* of said Fig. 1.

Letters of like name and kind refer to like parts in each of the figures.

The design of my invention is to increase the durability and improve the operation of a reversible-flue furnace; and it consists principally in a detachable fire-pot, connected with a furnace in such manner as to enable it to expand and contract vertically under the influence of heat, without interference with or change of the relative positions of other portions of said furnace, substantially as and for the purpose hereinafter specified. It consists, further, in a reversible-flue furnace having descending flues which decrease in transverse dimensions from their upper to their lower ends, substantially as and for the purpose hereinafter shown. It consists, further, in a reversible-flue furnace having ascending or return flues which pass through the combustion-chamber, substantially as and for the purpose hereinafter set forth. It consists, further, in the combination of the cross-flues with the dome-plate, substantially as and for the purpose hereinafter shown and described.

In the annexed drawings, A represents the base-plate of my furnace, upon which is an ash-pit, B, of usual form, and around the sides and rear of said ash-pit is placed a bottom-flue, C, which is, preferably, formed upon a circular line.

Upon the ash-pit B is placed a fire-pot, D, and above the latter a drum, E, which forms the combustion-chamber, and is supported by

means of flues F F, &c., which extend between the lower side of the same, near its outer edge, and the bottom flue C.

The flues F and F convey the heated gases of combustion from the combustion-chamber to the bottom flue, and have regularly decreasing dimensions from their upper to their lower ends, by which means the velocity of the current of said gases is rendered uniform, such decrease in the transverse area of said downward flues being equal to the lessened volume of said gases caused by the loss of heat as they recede from the incandescent fuel.

At a suitable point upon each side of the furnace, and, preferably, in rear of its center, is provided a return or ascending flue, G, which extends from the bottom flue C vertically upward through the combustion-chamber E and terminates at the upper side of the same within a cross-flue, H.

The ascending flue G is parallel and has transverse dimensions nearly equal to the combined areas of the lower ends of the descending flues F and F upon its side of the heater, so as to afford free upward passage for the heated gases, which, through said flues, reach the bottom flue C.

By the passage of the flue G through the combustion-chamber E, the gases within such portion of said flue have their temperature increased and, by expansion, are caused to ascend with much greater velocity than would be the case were said pipes exposed to the chilling currents of air around the heater, such arrangement giving a strong and uniform draft.

The cross-flue H is formed upon the upper side of the dome-plate E', and extends from the upper end of the return-flue G inward to the center of said plate, where it unites with a like flue from the opposite side, and opens upward into an exit-flue, I, and downward through a dampered opening, E'', into the combustion-chamber E.

The location of the cross-flues H and H causes the gases passing through the same to retain their temperature, and prevents their velocity from becoming checked.

The fire-pot D rests upon the upper side of the ash-pit B, and has its lower end contained within, or caused to embrace, an upwardly-projecting flange, b, as may be desired. The upper end of said fire-pot fits within a corresponding opening in the lower side of the drum E, and has, preferably, an outwardly-projecting flange, d, which extends beyond said opening and prevents the downward passage of dust and ashes.

As thus arranged, it will be seen that the vertical expansion and contraction of the fire-pot in no manner affect the relative positions of the contiguous portions of the furnace, such changes of position of said parts being entirely independent.

I am aware of the patent of Gardner Chilson, No. 11,718, of September 26, 1854, in which are shown ascending flues that decrease in transverse dimensions from their lower to their upper ends, and hereby disclaim such construction.

Having thus fully set forth the nature and merits of my invention, what I claim as new is—

1. In a heating-furnace, the combination, with the ash-pit B, combustion-chamber E, and with the inclosed air-heating space between said parts, of the fire-pot D, which is supported by said ash-pit, and has its lower

end contained within the vertical annular flange b and at its upper end projects through the lower plate of said combustion-chamber, and is provided with an outwardly-projecting flange, d, substantially as and for the purpose specified.

2. In combination with the combustion-chamber E and with the bottom flue C, descending flues F and F, which extend between the same, and decrease in transverse dimensions from their upper to their lower ends, substantially as and for the purpose shown.

3. In combination with the combustion-chamber E of a revertible-flue furnace, an ascending flue, G, which passes upward through said chamber, substantially as and for the purpose set forth.

4. In combination with the combustion-chamber E, return-flues G and G, and exit-flue I, the cross-flues H and H formed upon the dome-plate E', and furnishing communication between said parts, substantially as and for the purpose shown and described.

In testimony that I claim the foregoing I have hereunto set my hand this 26th day of April, 1875.

MICHEL G. FAGAN.
